CLAIM

The ornamental design for a transducer mount, as shown and described.

DESCRIPTION

FIG. 1 is a front perspective view of a transducer mount according to the present invention;

FIG. 2 is a rear perspective view of the transducer mount;

FIG. 3 is a front view of the transducer mount;

FIG. 4 is a rear view of the transducer mount;

FIG. 5 is a left side view of the transducer mount;

FIG. 6 is a right side view of the transducer mount;

FIG. 7 is a top view of the transducer mount; and,

FIG. 8 is a bottom view of the transducer mount.

(Continued)

The broken lines shown in the drawings represent portions of the transducer mount that form no part of the claimed design.

1 Claim, 5 Drawing Sheets
